CLAIM

The ornamental design for a gold bar greeting card, as shown and described.

DESCRIPTION

FIG. 1 is a front view of a card showing my new design; FIG. 2 is a rear view thereof; FIG. 3 is a left elevational view thereof with the right elevational view being identical thereto; and, FIG. 4 is a top plan view thereof with the bottom plan view being identical thereto.

The long and short broken lines represent a fold line, shown in FIGS. 1-2, are part of the claimed design. The evenly spaced broken lines representing indicia and text shown in FIGS. 1-2 are for illustrative purposes only and form no part of the claimed design.
